(57) **CLAIM**

(21) Appl. No.: **29/258,346**

We claim the ornamental design for a light for illuminating fluorinated fishing line, as shown and described.

(22) Filed: **Apr. 21, 2006**

DESCRIPTION

(30) **Foreign Application Priority Data**

Nov. 24, 2005 (JP) 2005-034535

FIG. 1 is a top perspective view of a light for illuminating fluorinated fishing line of the present invention;

(51) **LOC (8) Cl.** 22-05

FIG. 2 is a front view thereof;

(52) **U.S. Cl.** D22/134

FIG. 3 is a first side view thereof;
